DESIGN FOR A COMBINED FIGURE DISPLAY AND CONTAINER

George L. Rosenfeld, Cleveland, Ohio

Application August 22, 1940, Serial No. 94,550

Term of patent 3½ years

To all whom it may concern:

Be it known that I, George L. Rosenfeld, a citizen of the United States, residing at Cleveland, in the county of Cuyahoga and State of Ohio, have invented a new, original, and ornamental Design for a Combined Figure Display and Container, of which the following is a specification, reference being had to the accompanying drawing, forming part thereof.

The ornamental design for a combined figure display and container, substantially as shown.
